UNITED STATES PATENT OFFICE.

JACOB H. WEISBROD, OF ST. LOUIS, MISSOURI, ASSIGNOR TO AMERICAN CAR AND FOUNDRY COMPANY, OF ST. LOUIS, MISSOURI, A CORPORATION OF NEW JERSEY.

UPPER BUFFING DEVICE FOR VESTIBULE FACE-PLATES.

1,170,587.

Specification of Letters Patent.

Patented Feb. 8, 1916.

Application filed March 18, 1915. Serial No. 14,781.

To all whom it may concern:

Be it known that I, JACOB H. WEISBROD, a citizen of the United States, residing at St. Louis, Missouri, have invented a certain new and useful Improvement in Upper Buffing Devices for Vestibule Face-Plates, of which the following is a full, clear, and exact description, such as will enable others skilled in the art to which it appertains to make and use the same, reference being had to the accompanying drawings, forming part of this specification.

My invention relates generally to railway car vestibules and more particularly to the means employed for maintaining the upper portions of the diaphragm face plates of vestibules in proper position or in restoring them to such position when they have been displaced or shifted as a result of relative movement between the cars to which the diaphragms are applied as said cars pass over curves, crossings and irregularities in the track.

Devices of the character to which my invention relates are usually known as upper buffing devices for vestibule face plates, and generally include a spring, preferably of the semi-elliptic type, and composed of one or more leaves, which spring is interposed between the face plate of the diaphragm and the end of the car, and which, in service, is compressed and expands with the corresponding movements of the diaphragm, thus at all times, maintaining the face plates of an adjacent pair of diaphragms in close yielding contact with each other.

The principal object of my invention is to provide comparatively simple and inexpensive connecting means between the semi-elliptic spring which is carried by the diaphragm face plate and the vestibule structure, which means is particularly effective in resisting the outward swinging movement of the upper portion of said diaphragm face plate.

The connecting means contemplated by my invention include spring bearings or brackets, each comprising a member which is adapted to be rigidly fixed to the car body while the same is under construction, and said member being adapted to receive a yoke or keeper, the same being attached to the fixed member by means of a readily removable bolt or pin and which yoke or keeper maintains the end portion of the

spring in proper operative position against the end of the vestibule and at the same time permits the spring to be readily removed and repositioned for use as may be required when the diaphragm is undergoing repairs.

With the foregoing and other objects in view, my invention consists in certain novel features of construction and arrangement of parts, hereinafter more fully described, claimed and shown in the accompanying drawings, in which—

Figure 1 is a top plan view of a portion of a railway car diaphragm and showing a bracket or bearing of my improved construction associated with the face plate buffing spring. Fig. 2 is a front elevational view of the parts seen in Fig. 1. Fig. 3 is an enlarged horizontal section taken approximately on the line 3—3 of Fig. 2. Fig. 4 is an enlarged vertical section taken approximately on the line 4—4 of Fig. 2.

Referring by numerals to the accompanying drawings, 10 designates the end portion of a car vestibule, 11 the usual bellows diaphragm, and 12 the usual face plate of said diaphragm. An ordinary semi-elliptic spring 13 having one or more leaves is fixed in any suitable manner at its center to the upper central portion of face plate 12.

The bracket as contemplated by my invention and which serves as a combined keeper and bearing for the end of the spring includes a base member, preferably in the form of a hollow block and comprising a vertically disposed face plate 14, horizontally disposed top and bottom plates 15 and 16, end walls 17, and ears 18, which latter are preferably formed integral with the end walls 17 and being adapted to receive rivets or like devices which rigidly fix the hollow block directly to the vestibule structure.

The spring keeper which is associated with the hollow block is channel-shape when viewed in end elevation and comprises a vertically disposed plate 19 with the ends of which are formed integral horizontally disposed plates 20, one of which overlies the top plate 15 of the hollow block and the other one underlying the bottom plate 16. Coinciding apertures are formed through plates 15, 16 and 20 and removably positioned therein is a vertically disposed pin or bolt 21, the lower end of which receives

a cotter pin 22 or like device which prevents the accidental displacement of said pin.

The parts of my improved device are proportioned so that the vertically disposed plate 19 of the keeper occupies a position a short distance in front of the bearing plate 14 of the hollow block, thus providing between said plates a space or pocket for the end portion of spring 13, it being understood that the outer ends of the latter are bent forwardly outside the bearings or bracket, thus providing stops to limit the inward movement of the end portions of the springs with respect to said brackets. In service the spring 13 yieldingly resists the inward movement of the face plate 12 and during such action the ends of the spring move freely through the spaces between the plates 19 and 14, the latter plates serving as bearings for the end portions of said spring.

While I have shown and described the upper buffering spring as being connected to the diaphragm face plate and the spring retaining brackets or keepers on the vestibule structure, it will be understood that the positions of these parts may be reversed, that is, with the spring secured to the vestibule structure and the brackets or keepers secured to the diaphragm face plate.

A device of my improved construction is comparatively simple, can be cheaply manufactured and installed, provides a substantial connection between the ends of the face plate buffering spring and the vestibule structure, readily permits the end portions of the spring to move freely in both directions as the spring is compressed and expands, and in the event of repairs or renewal of the diaphragm, the keepers can be easily and quickly removed to permit the release of the end portions of the spring.

It will be readily understood that minor changes in the size, form and construction of the various parts of my improved device can be made and substituted for those herein shown and described, without departing from the spirit of my invention, the scope of which is set forth in the appended claims.

I claim:

1. The combination with a railway car vestibule and vestibule diaphragm face plate, of a semi-elliptic spring secured to one of said elements, and bearings for the free ends of said springs, each of which bearings comprises a fixed block upon which the free end of the spring bears, and a clevis-shaped keeper applied to said block and inclosing the end of the spring.

2. The combination with a railway car vestibule and vestibule diaphragm face

plate, of a semi-elliptic spring secured to one of said elements, and spring bearings fixed to the other element, each of which bearings comprises a bearing member against the face of which the free end of the spring 65 engages and a clevis-shaped keeper detachably applied to said bearing member and inclosing the free end of said spring.

3. The combination with a railway car vestibule and vestibule diaphragm face 70 plate, of a semi-elliptic spring secured to one of said elements, and spring bearings fixed to the other element, each of which bearings comprises a member having a bearing plate against the face of which the free end of 75 the spring engages and a substantially channel-shaped keeper detachably applied to said bearing plate, with the legs of said keeper applied to the top and bottom of said plate.

4. The combination with a railway car 80 vestibule and vestibule diaphragm face plate, of a semi-elliptic spring secured to one of said elements, and spring bearings fixed to the other element, each of which bearings comprises a member provided with a bearing 85 plate against the face of which the free end of the spring engages, a substantially clevis-shaped keeper the legs of which engage the top and bottom of said bearing plate and readily removable attaching means seated in 90 the keeper and bearing plate.

5. A diaphragm face plate spring retaining device comprising a bearing plate against which the free end of the spring is adapted to engage, a keeper applied thereto, 95 said parts being spaced apart to form a spring pocket in which the free end of the spring is loosely mounted and a detachable member for securing said keeper to the bearing plate.

6. A diaphragm face plate spring retaining device comprising a spring bearing plate against which the free end of the spring engages, a substantially channel-shaped keeper applied thereto, and fastening means seated 105 in said keeper and plate.

7. A diaphragm face plate spring retaining device comprising a block having a spring bearing face, a keeper having parts overlying and underlying said block, and 110 fastening means seated in said block and the overlying and underlying portions of the keeper.

In testimony whereof I hereunto affix my signature in the presence of two witnesses, 115 this first day of March, 1915.

JACOB H. WEISBROD.
